GIOVANNI BOSCARELLI, OF LONDON, ENGLAND.

PROCESS FOR ROLLING THIN OR MIDDLE SHEETS FROM SHEET BARS.

Application filed June 20, 1923, Serial No. 646,686, and in Great Britain July 21, 1922.

The present invention relates to an improved process for rolling thin or middle sheets from sheet bars.

The present invention is designed to provide means to render unnecessary the second heating and second rolling processes before the superimposed sheets are doubled, as necessary in the sheet rolling process now employed.

10 In the process hitherto in use, two sheet bars only are manipulated at the same time by two operators who are usually known as the "roller" and the "catcher." The "roller" takes the first of a pair of sheet bars and passes it through the rolls to the "catcher" who receives the rolled sheet with a pair of tongs and holds it above the rolls while the "roller" is passing the second sheet bar through the rolls. The "roller" then takes the first sheet bar from the "catcher" who then receives the second sheet bar with his tongs and holds it in position for the "roller" to take it after he has again passed the first sheet bar 25 through the rolls. After the pair of sheet bars have been passed through the rolls for a sufficient number of times they are superimposed and in this form passed through the rolls again until they are too cold to 30 be extended and reduced in thickness by rolling. They are then placed in the furnace to be reheated while a second pair of sheet bars are passed through the rolls in the same manner. When this second pair of 35 sheet bars have been rolled out to the same dimensions as the first pair, one of these sheet bars is superimposed on the sheet formed from the first pair of bars which are being reheated in the furnace and when 40 sufficiently hot the three superimposed sheets are again passed through the rolls a sufficient number of times to obtain a combined or three leaf sheet of such dimensions as to allow of its being doubled when the combined sheet is again reheated in the furnace and again passed through the rolls in doubled form until it is finally reduced to the desired dimensions.

According to the present invention three 50 or more sheet bars are manipulated simultaneously in such a manner that the intermediate heating now necessary when the first pair of sheet bars have been superimposed and are cold and the second pair of sheet bars are being passed through the rolls, is done away with and also the sec-

ond rolling process now necessary when the sheets are superimposed, to obtain the desired dimensions for doubling.

The method of carrying out my process 60 is shown by way of example in the accompanying drawings, in which—

Figures 1 to 3 show diagrammatically the method of carrying out the process.

Referring now to Figure 1, which illustrates more particularly the method carried out for three sheet bars. The sheets are numbered 1, 2 and 3 the respective numbers referring to the same sheet in each diagram forming Figure 1. The "roller" passes sheet 1 through the rolls as at A, where it is taken by the "catcher" and raised by him over the upper roll, as at B, while the "roller" passes sheet 2 through the rolls. The "roller" then takes sheet 1 from the "catcher" and places it behind sheet 3 while the "catcher" takes sheet 2 as at C. The "roller" passes sheet 3 through the rolls while the "catcher" raises sheet 2 over the upper roll as at D. The "roller" then takes sheet 2 from the "catcher" and places it behind sheet 1 while the "catcher" is taking sheet 3 as at E. Sheet 3 is raised by the "catcher" while the "roller" passes sheet 1 through the rolls once more as at F, and takes sheet 3 from the "catcher" and places it behind sheet 2, while the "catcher" takes sheet 1 as at G. The three bars are passed through the rolls in order, in this manner a sufficient number of times to obtain the desired dimension, when they are superimposed by the "roller" on receiving them from the "catcher" over the upper roll as at H and then passed together through the rolls in this combined leaf form, 95 still without further heating, until rolled to the desired dimension when they are doubled and reheated in the usual manner, before the sheet composed of six superimposed leaves thus formed by doubling the three 100 leaf sheet is passed through the rolls again to be reduced in thickness to its final dimensions. It should be understood that in contradistinction to those three sheet bar processes hitherto suggested, only two men are 105 employed to manipulate the bars.

Referring now to Figure 2, this shows my method carried out for four sheet bars. The sheets are numbered 1, 2, 3 and 4, the respective numbers referring to the same sheet in each diagram forming Figure 2. The "roller" commences with four sheets con-

veniently and preferably arranged in two groups, one behind the other as at A. He passes sheets 1 and 2 consecutively through the rolls as at B and C, the "catcher" taking sheets 1 and 2 together as the "roller" moves sheet 3 in the rolls. The "catcher" then raises sheets 1 and 2 while sheets 3 and 4 are being passed through the rolls as at D. They are then taken by the "roller" over the upper roll as soon as sheet 4 has passed through the rolls, as at E. The "catcher" commences to raise sheets 3 and 4 while sheet 2 is passing through the rolls as at F and has completely raised them over the upper roll when sheets 1 and 2 have both been passed through the rolls as at G. This process is continued, the bars passing singly through the rolls till the desired dimensions are obtained the whole four then being piled by the "catcher" as at H and J and then passed back as a group over the upper roll as at J. They are then rolled together without the necessity of heating as at K until the desired dimensions for doubling and reheating are reached.

It will be seen that by this method, though the sheets are rolled singly they are lifted and lowered in pairs, so that the "catcher" has the time to lift the pair while the other pair are passing consecutively through the rolls, that is approximately twice the time allowed in the method of rolling two sheets at present used, the only special precaution necessary being that the "catcher" must commence the lift as soon as possible to clear the guides for the reception of the next sheet.

Referring now to Figure 3, this shows my method carried out for six sheet bars. The sheets are numbered 1, 2, 3, 4, 5 and 6, the respective numbers referring to the same sheet in each diagram forming Figure 3. The "roller" commences with the six sheets conveniently and preferably arranged in two groups of three, one behind the other as at A. He passes sheets 1, 2 and 3 in succession through the rolls as at B, C and D and they are taken by the "catcher" who commences to raise them together as sheet 4 comes through the rolls, as at E. The "catcher" continues to raise the three sheets until he has lifted them over the upper roll where they are taken by the "roller" when the three sheets 4, 5 and 6 have passed through the rolls as at C. The "catcher" then lifts sheets 4, 5 and 6 together during the time that sheets 1, 2 and 3 are again passed consecutively through the rolls as at H, J, K and L. The process is repeated a sufficient number of times and when the sheets have been rolled singly in the desired dimensions, the whole six are piled by the "catcher" as at H and N, passed back to the "roller" over the upper roll as at C and rolled together without the necessity of reheating,

as at P until the desired dimensions for doubling and reheating are reached. It will be seen that by this method, though the sheets are rolled singly they are lifted and lowered in threes, so that the "catcher" has the time to lift the three sheets together while the other three are passing consecutively through the rolls, that is approximately three times the time allowed in the method of rolling two sheets at present used, the only special precaution necessary being that the "catcher" must commence the lift as soon as possible to clear the guides for the reception of the next sheet.

In both of the two latter systems described above, not only is the length for doubling acquired without the necessity for reheating the roughed out sheets, but it is proved in working that production is greatly increased, as four or six sheet bars, instead of two, are rolled out simultaneously. In fact, the time occupied in extending four or six sheet bars to the length for doubling is approximately the same as that taken to extend only two sheet bars to the shorter length of singled out sheets, by the method at present in use. The reheating operations and all the necessary and costly operations in connection with this, are completely eliminated, the first heating applied to the sheet bars being fully utilized.

The four sheet bar method is used preferably to roll sheets of standard gauges lower than No. 30 ($\frac{1}{16}$ mm. or more in thickness). Sheets of gauges between No. 30 and No. 36 are more easily rolled by the six sheet bar method.

Although the methods above described are adapted to be successfully carried out entirely by hand, I prefer to provide a mechanical device for lifting the groups of sheets on the "catcher" side of the rolls.

It will be obvious that the lifting bars 3 must be made long enough to clear the greatest length the sheets attain during the roughing out process when they are rolled consecutively. When the groups are rolled together to the length for doubling, they may extend beyond the lifting rods 3 onto the frame 1, so there will be no sheets to clear on the descending stroke the whole number of sheets being lowered by the "roller" on his side of the rolls, while the frame is descending on the "catcher's" side.

What I claim is:—

1. A method for producing middle or thin sheets from sheet bars, in which the necessity for intermediate heating is avoided and the time for production reduced, comprising the rolling consecutively of a plurality of sheet bars to the desired dimensions, piling them together and rolling again in this combined leaf form to the desired dimensions without further heating, doubling the said combined sheet and then reheating the doubled sheet

thus formed and finally rolling the said combined doubled sheet to the desired dimensions.

2. A method for producing middle or thin sheets from sheet bars in which the necessity for intermediate heating is avoided and the time for production reduced, comprising rolling consecutively four sheet bars to the desired dimensions, piling said sheet bars in pairs and rolling said pairs again in this combined form to the desired dimensions, superimposing said pairs and rolling again in the combined form, doubling the said combined sheet and then reheating the doubled sheet thus formed and finally rolling the said doubled sheet to the desired dimensions.

3. A method for producing middle or thin sheets from sheet bars in which the necessity for intermediate heating is avoided and the time for production reduced, comprising the rolling consecutively of a plurality of sheet bars to the desired dimension, piling them together and rolling again in this combined leaf form to the desired dimensions without further heating, mechanically lifting the combined sheet on the catcher side of the

rolls, in order that they may be passed over the rolls to doubling and heating means, doubling the said combined sheet and then reheating the doubled sheet thus formed and finally rolling the said combined doubled sheet to the desired dimensions.

4. A method for producing middle or thin sheets from sheet bars, in which the necessity for intermediate heating is avoided and the time for production reduced, comprising rolling consecutively four sheet bars to the desired dimensions, piling said sheet bars in pairs and rolling again in this combined form to the desired dimensions, mechanically lifting the groups of sheet bars on the "catcher" side of the rolls, in order that they may be passed over the rolls to doubling and heating means, superimposing said pairs and rolling again in the combined form, doubling the said combined sheet and then reheating the doubled sheet thus formed and finally rolling the said combined doubled sheet to the desired dimensions.

In testimony whereof I have signed my name to this specification.

GIOVANNI BOSCARELLI.
